SHOE AND SHANK STIFFENER AND METHOD
OF ATTACHING THE LATTER

Le Roy W. Rollins, West Medford, and Arthur S. Johnson, Beverly, Mass., assignors to United Shoe Machinery Corporation, Paterson, N. J., a corporation of New Jersey

Application April 17, 1931. Serial No. 530,914

22 Claims. (Cl. 36—76)

This invention relates to improvements in shoes and shank stiffeners therefor and to improved methods of attaching shank stiffeners.

In the manufacture of shoes having shank stiffeners located between inner and outer soles it is customary to employ fastening means such as tacks or prongs for securing the stiffeners to the inner soles to insure that the stiffeners will be permanently retained in the proper locations in the shoes. In order that the tacks or prongs shall provide a sufficiently secure bond they are usually passed entirely through the insole of the shoe and clenched over the inner surface of the insole. This practice is often undesirable, however, inasmuch as the clenched-over ends of the prongs or tacks mar the appearance of the inside of the shoe and are liable to wear holes in the sock lining and in the stocking of the wearer of the shoe.

One object of the present invention is to provide for the secure fastening of a shank stiffener to an insole or corresponding shoe bottom member in an improved and practical manner and without employing fastening members which extend through to the inside of the shoe.

With this object in view, one feature of the invention consists in the provision of an improved method of attaching shank stiffeners which consists in placing a shank stiffener upon a sole, positioning a staple with its legs straddling a portion of the stiffener, and forcing the legs of the staple into the sole in converging directions to clench them within the material of the sole beneath the head of the staple. As herein illustrated the staple legs are driven through spaced apertures in the stiffener and are deflected toward each other, as they are being driven, by contact with converging deflecting surfaces formed in the walls of the apertures in the stiffener, the deflecting surfaces being constructed and arranged to cause the points of the staple legs to curl inwardly and clench beneath the head of the staple in such a manner as most effectively to resist displacement and thus securely to hold the stiffener in place.

In accordance with another feature of the invention there has been provided an improved shank stiffener having fastener deflecting surfaces constructed and arranged to deflect fastener members toward each other as they are being driven into a sole to which the stiffener is to be attached. In the illustrated embodiment of this feature of the invention two oppositely inclined fastener deflecting surfaces are arranged adjacent to a pair of passages in the

stiffener through which the legs of a staple may be driven, these inclined surfaces sloping inwardly and being arranged to deflect the legs of the staple toward each other so that they will clench within the material of the insole and beneath the head of the staple in a manner firmly to secure the stiffener in place without, however, extending through to the inner surface of the insole. Furthermore, in order to provide for more secure attachment to an insole, the illustrated stiffener is provided with a pair of passages or apertures and associated deflecting surfaces in each end portion of the stiffener and the passages of each pair are connected by a groove in the outsole-engaging surface of the stiffener in which the crosspiece of the staple is adapted to be countersunk so as to be substantially flush with the outsole-engaging surface of the stiffener.

Considered in another aspect, the invention, as herein illustrated, resides in a shoe having an inner sole and an outer sole, a shank stiffener located between the soles, and formed with a pair of passages providing converging, fastener-deflecting surfaces, and fastener members extending through those passages and into the inner sole, the fastener members having portions engaging the deflecting surfaces and sloping toward each other and away from the stiffener and being clenched within the material of the inner sole.

The invention will be explained with reference to the accompanying drawing, in which

Fig. 1 is a plan view of the upper or insole-engaging side of a shank stiffener made in accordance with the present invention;

Fig. 2 is a side elevational view of the shank stiffener showing it in assembled relation with the insole of a shoe;

Fig. 3 is a fragmentary sectional view taken along the line III—III of Fig. 1;

Fig. 4 is a plan view of the lower or outsole-engaging side of the stiffener;

Fig. 5 is a view similar to Fig. 4 but showing the stiffener as it appears when stapled to an insole;

Fig. 6 is a view, in central longitudinal section and on an enlarged scale, of one end portion of the stiffener showing it as it appears when stapled to an insole;

Fig. 7 is a cross-sectional view of the shank portion of a shoe having the improved stiffener embodied therein;

Fig. 8 is an enlarged plan view of one end portion of the stiffener;

Fig. 9 is a sectional view taken along the line IX—IX of Fig. 8; and

Fig. 10 is a plan view of one end portion of a stiffener embodying a modification of the present invention.

Referring to the drawing, the improved shank stiffener comprises an elongated metallic strip 12 having the usual longitudinal curvature shown in Fig. 2. To enable the shank stiffener to be attached to a shoe sole, such as the insole shown at 14, by means of fastener devices, such as the staples 16, the stiffener strip 12 is provided at each end portion thereof with a pair of passages 18 for receiving the legs of the staples. As illustrated in Figs. 1 to 9, inclusive, the passages 18 are spaced apart lengthwise of the stiffener strip so that the crossbars or heads of the staples will extend longitudinally of the stiffener, this construction having been found best adapted for use in relatively narrow stiffener strips, such as those commonly employed in many types of women's shoes. In wider stiffener strips, however, it may be desirable to space the passages 18 widthwise of the stiffener strip, as shown in Fig. 10, so that the crossbars of the staples will be disposed transversely of the stiffener strip. The passages 18 are formed with inner side walls 20 (Fig. 6) which are substantially perpendicular to the surfaces of the stiffener strip and, in order to insure that the legs of the staple shall be deflected inwardly so as to clench within the material of the insole, instead of extending entirely through the insole, the passages 18 are formed also with flaring outer side walls shaped and arranged to provide, in connection with each passage, a relatively large triangular entrance opening 24 at the outsole-engaging side of the stiffener strip, a relatively small approximately circular outlet opening 26, in line with the inner side wall 20, at the insole-engaging side of the stiffener strip, and deflecting surfaces 22 which slope downwardly toward the opening 26 and terminate in a curved portion 23 arranged to curl the points of the staple legs toward the head of the staple. In addition to sloping as above described, the portions of the outer side walls of the passage 18 at opposite sides of the longitudinal center line of the stiffener strip also slope inwardly toward said center line, as indicated at 25, 25 in Fig. 9. Thus, as best shown in Figs. 6, 8 and 9, the sloping outer side walls of the passages 18 constitute trough-like depressions shaped and arranged to receive the pointed ends of the staple legs and to direct them toward the relatively small openings 26. To insure proper clenching of the staple legs in the material of the insole, these trough-like depressions are formed so that the sloping outer side walls of the passages 18 extend to points outwardly offset from the insole-engaging side of the stiffener strip, thus facilitating the clenching of the staple legs in a manner to insure secure attachment of the stiffener to the insole. The formation of the trough-like depressions constituting the outer side walls of the passages 18 results in striking up projections or spurs 28 at the insole-engaging side of the stiffener strip which function, by embedding themselves in the material of the insole, to assist in preventing edge-wise displacement of the stiffener strip after the latter has been attached to the sole. As shown, the passages 18 are connected, at the outsole-engaging side of the stiffener strip by a shallow groove 30 adapted to receive the crossbar or head 32 of the staple. This construction enables the heads of the staples to be countersunk in the stiffener strip so that they will be flush or substantially flush with the surface of the strip so

as not to interfere with the laying and leveling of the outsole.

When a staple is driven through the passages 18 the inner ends of the legs of the staples will be deflected inwardly or toward each other by the inclined surfaces 20 so that the staple legs will clutch within the material of the insole between the inner and outer surfaces thereof, the construction and arrangement of the deflecting surfaces being preferably such as to cause the points of the staples to curl inwardly and clutch beneath the head of the staple, as best shown at 34 in Fig. 6, and the head 30 of the staple will be countersunk within the groove 30, thus enabling the outsole to be laid in close contact with the outer face of the stiffener strip. The relation of the stiffener strip to the other parts of the shoe is best shown in Fig. 7 wherein 36 indicates the upper materials of the shoe, 38 the outsole, and 40 the stitching which unites these parts with the insole 14.

In attaching the stiffener strip 12 it is preferable to employ staple driving mechanism having means for locating the strip relatively thereto, such as that described and claimed in United States Letters Patent No. 1,904,314, granted April 18, 1933, upon application of Arthur S. Johnson.

Having described our invention, what we claim as new and desire to secure by Letters Patent of the United States is:

1. That improvement in methods of attaching shank stiffeners which consists in placing a shank stiffener upon a sole, positioning a staple with its legs straddling a portion of the stiffener, and forcing the legs of the staple into the sole in converging directions to clench them within the material of the sole beneath the head of the staple.

2. That improvement in methods of attaching shank stiffeners which consists in placing a shank stiffener upon a sole, positioning a staple fastener with its legs straddling a portion of the stiffener, and driving the legs of the staple into the sole while deflecting them inwardly toward each other and embedding the end portions of the legs in the sole.

3. A shank stiffener having fastener-deflecting surfaces constructed and arranged to deflect fastener members toward each other as said members are driven into a shoe sole.

4. A shank stiffener having a pair of oppositely inclined fastener-deflecting surfaces constructed and arranged to deflect the legs of a staple fastener toward each other so that they will clutch within the material of a sole to which the shank stiffener is to be applied.

5. A shank stiffener comprising a longitudinally arched strip having a pair of passages for receiving fastener members constructed and arranged to provide oppositely inclined surfaces sloping inwardly toward the longitudinally convex side of the strip to deflect said fastener members toward each other as they are being driven through said passages.

6. A shank stiffener provided with a pair of spaced passages with oppositely inclined surfaces adjacent to opposite sides of said passages, said surfaces sloping inwardly and arranged to deflect toward each other the legs of a staple driven through said passages, the surface at one side of the stiffener being relieved between said passages to receive the crosspiece of the staple.

7. A shank stiffener having fastener-deflecting surfaces constructed and arranged to deflect the legs of a staple fastener toward each other so that they will clutch within the material of a sole to

- which the shank stiffener is to be applied, and a groove located between said deflecting surfaces for receiving the crossbar of the staple. 8. A shank stiffener having two spaced passages extending therethrough for receiving the legs of a staple fastener, said passages being connected by a groove at one side of the stiffener for receiving the crosspiece of the staple, and a surface adjacent to each passage inclined to deflect inwardly the legs of the staple as they are being driven therethrough. 9. A shank stiffener comprising an elongated strip having in each end portion a pair of spaced passages with oppositely inclined surfaces at the opposite sides of said passages, said surfaces sloping inwardly and arranged to deflect toward each other fastener members driven through said passages. 10. A shank stiffener comprising a narrow strip having in each end portion a pair of passages spaced apart lengthwise of the strip and having oppositely inclined surfaces adjacent to the opposite sides of said passages, said surfaces sloping inwardly and arranged to deflect toward each other fastener members driven through said passages. 11. A shank stiffener comprising a strip having two spaced passages extending therethrough for receiving fastener members, each of said passages having substantially perpendicular inner side walls and flaring outer side walls constructed and arranged to provide a relatively large inlet at one side of the stiffener strip and a relatively small outlet at the other side of the strip, and a deflecting surface in the line of drive of the staple legs, said deflecting surface and said outlet being shaped and arranged to cause the staple legs to clinch within the material of a sole to which the stiffener is applied. 12. A shank stiffener having two spaced apertures therein for receiving fastener members and having trough-like depressions adjacent to said apertures shaped and arranged to receive the ends of said fastener members and to guide them through said apertures in directions toward each other. 13. A shank stiffener having two spaced passages extending therethrough for receiving the legs of a staple fastener and having triangular depressions adjacent to opposite sides of said apertures, said depressions providing oppositely inclined surfaces at one side of the stiffener for guiding the legs of the staple toward each other and through said passages and projections at the opposite side of the stiffener for entering a sole to which the stiffener is attached. 14. A shank stiffener comprising a strip having in each end portion a pair of passages spaced apart lengthwise of the strip and having oppositely inclined surfaces adjacent to the opposite sides of said passages, said surfaces being shaped and arranged to align the legs of the staples with the longitudinal center line of the stiffener. 15. A shank stiffener comprising a strip having in each end portion a pair of passages spaced apart lengthwise of the strip and having oppositely inclined surfaces adjacent to the opposite sides of said passages, said surfaces sloping both lengthwise and crosswise with respect to a line connecting said passages for the purpose of guiding the legs of the staples into said passages and deflecting the staple legs toward each other so that they will clinch within the material of the sole. 16. A shank stiffener having a pair of passages for receiving the legs of a staple and curved deflecting surfaces adjacent to said passages constructed and arranged to cause the ends of the staple legs to curl toward the head of the staple. 17. In a shoe having an inner sole and an outer sole, a shank stiffener located between the soles and having converging fastener-deflecting surfaces, and a staple fastener member having portions engaging said deflecting surfaces and extending toward each other into the body of the inner sole. 18. In a shoe having inner and outer soles, a shank stiffener located between the soles and provided with a pair of passages providing converging fastener-deflecting surfaces, and fastener members extending through said passages and into the inner sole, said members having portions engaging said deflecting surfaces and sloping toward each other and away from said stiffener and being clenched within the material of the inner sole. 19. In a shoe having inner and outer soles, a shank stiffener located between the soles and having in each end portion of the stiffener a pair of passages providing converging fastener-deflecting surfaces, and a staple fastener associated with each of said pairs of passages and arranged with its legs extending through said passages and into the inner sole, said staple legs engaging said deflecting surfaces and sloping toward each other and away from the stiffener and being clenched between the surfaces of the inner sole. 20. The combination of a sole, an elongated shank stiffener in engagement therewith having converging fastener-deflecting surfaces inclined lengthwise of the stiffener, and a fastener member having portions engaging said deflecting surfaces and sloping toward each other, said portions extending into the sole in directions determined by the said deflecting surfaces. 21. The combination of a sole, a shank stiffener in engagement with the sole, said stiffener being provided with two spaced passages and having a pair of inclined converging fastener-deflecting portions adjacent to said passages projecting into the sole to insure against relative edgewise displacement of the sole and the stiffener, and fastener members extending through said passages and into the sole, said members having portions engaging said deflecting surfaces and sloping toward each other. 22. In a shoe having an inner sole and an outer sole, a shank stiffener located between the soles and secured to the inner sole by means of a fastener member extending through the stiffener and having an end portion clenched within the material of the inner sole without passing through the inner sole, and fastener-deflecting means on the shank stiffener embedded in the inner sole. 70 80 85 90 95 100 105 110 115 120 125 130 135 140 145 150
